CLAIM

The ornamental design for an aerosol generator core as
shown and described.

DESCRIPTION

FIG. 1 is a perspective view of an aerosol generator core
according to the present invention.

FIG. 2 is a front elevational view of the aerosol generator
core depicted in FIG. 1.

FIG. 3 is a rear elevational view of the aerosol generator core
depicted in FIG. 1.

FIG. 4 is a right side elevational view of the aerosol
generator core depicted in FIG. 1.

FIG. 5 is a left side elevational view of the aerosol generator
core depicted in FIG. 1.

FIG. 6 is a top plan view of the aerosol generator core
depicted in FIG. 1; and,

FIG. 7 is a bottom plan view of the aerosol generator core
depicted in FIG. 1.

The broken lines in the drawings illustrate portions of the
aerosol generator core that form no part of the claimed
design.
